UNITED STATES PATENT OFFICE.

WILLIAM S. FERGUSON, OF LEESVILLE, LOUISIANA, ASSIGNOR OF ONE-HALF TO JAMES BEDFORD STERNS, OF VERNON PARISH, LOUISIANA.

ROTARY ENGINE.

No. 927,227.

Specification of Letters Patent.

Patented July 6, 1909.

Application filed March 16, 1908. Serial No. 421,351.

To all whom it may concern:

Be it known that I, WILLIAM S. FERGUSON, a citizen of the United States, residing at Leesville, in the parish of Vernon and State of Louisiana, have invented a new and useful 5 Rotary Engine, of which the following is a specification.

This invention has reference to improvements in rotary engines, and its object is to 10 provide an engine of this type wherein the rotor carries a sliding vane or piston and the steam course is so related to the rotor and sliding piston that no valves are needed to control the steam.

15 The invention comprises a stationary member composed of a cylindrical casing with heads secured thereto and so shaped on their contiguous faces as to form a steam course generally sinuous throughout its 20 length but with walls so spaced as to receive between them an annular rotary member of constant width throughout its length. The 25 annular member carries a number of sliding pistons mounted therein to move across the rotor parallel to the axis thereof in conformity to the sinuosities of the steam course. By properly locating inlet and 30 exhaust openings the steam is made to act upon the sliding piston first on one side of the 35 rotor and then on the other side thereof in a manner to drive the rotor always in the same direction. Provision is also made for the reversal of the direction of rotation of the 40 rotor by other properly located inlet and exhaust openings for the steam so that the latter will engage the pistons on the faces remote from those first engaged, thus impelling the rotor in a direction contrary to that in which it was first considered.

45 The sliding piston is made up of a number of separately movable plates or laminae so constructed as to always present a practically steam tight junction with the walls of the steam course without the necessity of any special type of packing.

The invention will be best understood by reference to the following detail description taken in connection with the accompanying drawings forming a part of this specification, 50 in which,—

Figure 1 is a side elevation, partly in section, of the improved rotary engine. Fig. 2 is a displayed plan of the steam course to an extent diagrammatically represented. Fig.

3 is a vertical section of the engine in a diametric plane coincident with the longitudinal axis of the power shaft. Figs. 4 and 5 are detail views, and Fig. 6 is a displayed view in diagram of a modified form of the steam course.

Referring to the drawings, there is shown a cylindrical casing 1 cast with or secured to a base 2. This casing receives at the ends two channel heads 3, 4, each formed on the inner face with an annular flange 5, the parts being 60 so proportioned that when the heads 3 and 4 are secured to the casing 1, as by bolts 6, the flanges 5—5 have their free edges close to each other but separated for a certain space. This space extends entirely around the circumference of the inner face of the two heads 70 3 and 4, which latter, together with the casing 1, constitute the stator of the machine. On each side of the casing, are suitable pedestals 7—7 formed at their upper ends with 75 journal boxes 8 for the reception of a shaft 9. This shaft has secured to it the hub 10 of a disk 11 extending through the space formed by the separated free ends of the flanges 5.

Each head 3 and 4, as measured in the direction of the length of the shaft 9, is for a portion of its length comparatively thin, as indicated at 12, and for the remainder of its length comparatively thick, as indicated at 13, in the structure indicated in Fig. 2. The 85 thin portion 12 and thick portion 13 each occupy about one-half the length of the head circumferentially and are joined by easy curves 14 and 15'. The heads are so related 90 that the portion 13 of one head is opposite the portion 12 of the other head, this forming a steam course 15 entirely around the stator. A certain part of the steam course indicated by the space between the longitudinal dotted lines of the diaphragm of Fig. 2 is of even 95 width throughout, one dotted line being coincident with the thicker portion 13 of the head 3 and the other dotted line with the thicker portion 13 of the head 4 so that on one side of the space defined by such dotted 100 lines there is a free space 16 extending circumferentially of the steam course coincident with the thicker portions 13 of the heads.

The disk or web 11 carries within the steam course an annular member 17 completely 105 filling the steam course in a radial direction and in width coinciding with the space between the longitudinal dotted lines of Fig. 2.

This annular member of the rotor is arranged to fit snugly and yet easily between the heads 3 and 4 within the space between the thicker portions 13 so that these thicker portions become fixed abutments between which the rotor revolves. At equidistant points about the annular member 17, say at four equidistant points as shown in Fig. 1, are lateral passages 18 extending entirely through the annulus 17 and in radial extent equal to the radial thickness of the steam course. Within these passages are sliding vanes or pistons made up of a number of plates 19, 20 and 21, each of which has a special function, as will presently appear.

The plates or laminae are in the particular instance shown substantially rectangular in outline so as to conform to the particular type of steam course although for other shapes of steam course these plates might be otherwise shaped in outline. The length of each of these plates is equal to the distance between the facing walls of the heads 3 and 4 defining the steam course, which distance is constant throughout the length of the steam course.

The plates 19 have rounded edges 22 where they bear against the inner walls of the heads 3 and 4 and may fit these walls snugly yet easily. The plates 20 are made up of two members between the contiguous ends of which is housed a spring 23 shown as a simple bow spring, but may be any type of spring adapted to the purpose. The spring 25 is designed to spread apart the two members of the plates 20 so that their outer edges may always be kept in firm contact with the walls of the heads 3 and 4, the tendency of the spring being to separate the two members of each plate 20 in the same direction as the longitudinal axis of the shaft 9. The outer end of each member of the plate 20 is made square, as indicated at 24, instead of rounded, as are the plates 19. The plate 21 has its edges engaging the side walls of the steam course rounded, as indicated at 25, like the rounded edges 22 of the plates 19. This plate, however, is split longitudinally into two members, and these members are urged in a direction radial to the rotor by a spring 26 so that the edges of the two members of the plate 21 engage the outer and inner walls of the steam course. By this means the sliding vane or piston is held in firm engagement with all the walls of the steam course and the connection thus made is practically steam tight.

Flanking the disk or web 11 on each side of the same adjacent to the point of entrance 60 of the web are rings 27 secured to the flanges 5 by suitable bolts 28. These rings are formed with annular grooves 29 on each of which is a packing ring 30 urged toward the side walls of the web 11 by set screws 31 be-

tween which and the packing is interposed a suitable ring 32.

Through the thickened portion 13 of the head 3 are steam passages 33 and 34 opening into the curved wall 15 near its point of merging into the straight portion of the thickened part 13. On the remoter sides of the steam inlet passages 33 and 34 are exhaust ports 35 and at points still more remote are other exhaust ports 36. Each exhaust port 35 and 36 is connected into a common exhaust passage 37. Extending through the like thickened portions of the head 4 are steam passages 38, 39, and exhaust ports 40, 41 merging into a common exhaust pipe 42 bearing the same relation to the head 4 as the other steam inlet and exhaust ports bear to the head 3. These several ports are connected up together exterior to the stator by suitable steam pipes 43 under the control of a suitable valve 44 and the exhaust passages are coupled up to the pipes 45 under the control of suitable valves 46.

Let it be assumed that the rotor is moving toward the right, as viewed in Fig. 2. Under these circumstances, the steam passage 39 and exhaust passages 41 and 42 are open. Also the steam passage 34 and exhaust ports 35 and 36 are open or acting. Suppose that the sliding piston be represented by a single plate 20 in Fig. 2. The steam entering through the pipe 39 will be brought into contact with this plate 20, but because the end of the plate is square and its angle is in contact with the corresponding wall of the steam course there is formed a substantially steam tight connection with no tendency to force this plate inwardly since the live steam cannot get around the end of the plate and so tend to compress the spring 23. The live steam therefore exerts a pressure upon the plate 20 tending to drive the rotor toward the right, as viewed in Fig. 2. The chamber on the active side of the plate 20 constantly increases because this plate is moving laterally into the part 16 of the steam course formed in the head 4 and the volume of steam acting on this plate is constantly increasing. As soon as the straight portion of the thick part 13 of the plate 3 is reached, then the lateral movement of the plate 20 ceases, while the onward movement of the rotor continues. Ultimately, the exhaust port 41 is reached, and the steam exhausts therethrough but in the mean time another piston has reached and passed the steam inlet 39 so that the steam on the active side of the plate 20 after the second sliding piston has reached the steam inlet 39, acts expansively. Any steam which may be in front of the plate 20 finds its way out of the exhaust port 41. As the plate 20 is moved in the reverse direction by the curve 15 adjacent to the steam ports 40 and 41, and after leaving the port 40 this plate

has been projected on the other side of the steam course where steam entering through the steam pipe 34 will act upon it in the same manner as already described for the steam entering through the steam pipe 39. In this way each end of the plate receives the active impulse of the steam during one revolution of the rotor.

While the foregoing description, especially with reference to the operation of the apparatus as described with relation to Fig. 2, has taken account of only one plate 20, it is to be observed that there is an intermediate or central plate 1 flanked on each side by a plate 20, and each plate 20 has next to it two plates 19. These last plates are provided for the purpose of suitably strengthening the sliding piston against which the entire force of the steam is exerted.

Attention has been called to the fact that one angle of the end of each plate 20 is adjacent to the active or steam side of the plate when the latter is moving toward the right, as viewed in Fig. 2. If, now, the direction of the rotor be reversed by changing the relation of the steam inlet and exhaust ports by a suitable manipulation of the valves 44 and 46, then the plates 20 moving toward the left, as viewed in Fig. 2, and the steam inlet pipes 33 and 38 becoming active, the engaging angle of these plates to the walls of the steam course is still adjacent to the active or steam side of the plates. Thus, under no circumstances is there danger of steam getting on the ends of the plates and so compressing the springs 23 and permitting the steam to escape by the plates.

It will be observed that the effective width of the steam course is considerably greater than the width of the annular member of the rotor and is arranged alternately on opposite sides of this annular member, while the sliding vanes or pistons are in length equal to the width of the steam course and slide through the annular member so as to become alternately effective on each side of the latter, the direction of movement of the pistons being parallel to the axis of the rotary member.

In Fig. 6, it is to be observed that the median section 15 of the steam course does not merge directly into the lateral extension 16 but approaches the same by a lateral extension 47 of less width than the member 16 so that steam engaging a piston entering the lateral extension 47 would expand when reaching the main section 16.

What is claimed is:-

1. A rotary engine provided with a steam course having the side walls curved at intervals to and from the longitudinal plane of the steam course, a movable vane or piston composed of a series of plates or laminæ in contact one with the other, and a rotary member in which the piston is mounted and entirely

across which it extends in a direction parallel with the axis of rotation of the said rotary member, with the plates of the said vane or piston independently movable in the direction of their length, the said vane or piston being active at each end in alternation. 70

2. In a rotary engine provided with a steam course having the side walls curved at intervals to and from the longitudinal plane of the steam course, a vane or piston made up of plates in yielding engagement with the walls of the steam course of the engine, and other plates of fixed length in direct contact with the yielding plates, all the plates being independently movable with relation to each other, and the plates of constant length being exterior to the yielding plates and of a length equal to the width of the steam course. 80

3. In a rotary engine, a stator provided with a steam course having lateral sinuosities, a rotor provided with an annular member housed in the steam course and in engagement with the side walls thereof at their points of closest approach to the median line, and vanes or pistons slidable laterally through and to each side of the movable member within the steam course, said vanes or pistons being made up of a number of independently movable plates or laminæ and active at each end in alternation. 95

4. In a rotary engine, a stator provided with a steam course having lateral sinuosities, a rotor provided with an annular member housed in the steam course and in engagement with the side walls thereof at their points of closest approach to the median line, and vanes or pistons slidable laterally through and to each side of the movable member within the steam course, said vanes or pistons being made up of a number of independently movable plates or laminæ, active ones of the plates having both ends constituting engaging ends in contact with the side walls of the steam course at an angle to the curved portions thereof. 110

5. In a rotary engine provided with a steam course, a sliding vane or piston made up of plates yieldable in a direction lateral to the length of the steam course, and plates of fixed length, all the plates being adapted to contact directly at both ends with the walls of the steam course, all of said plates being in side contact and independently movable. 115

6. In a rotary engine provided with a steam course, a sliding vane or piston made up of plates yieldable at right angles to each other and lateral to the length of the steam course, and other plates of fixed width and length, all of said plates being adapted to contact at both ends directly with the walls 125 of the steam course, and all of said plates being movable independently one of the other.

7. In a rotary engine provided with a

- steam course, a sliding vane or piston made up of a number of independently movable plates in direct side contact and including plates yieldable at right angles to the length 5 of the steam course, said yieldable plates being interior to the other plates and provided with engaging edges arranged in planes at right angles to the axis of rotation of the rotor of the engine.
- 10 8. A rotary engine provided with a steam course having the side walls curved at intervals to and from the longitudinal plane of the steam course, and sliding vanes or pistons made up of a number of plates movable laterally across the steam course and coextensive in length with the width of the steam course, said vanes or pistons including plates yieldable in the direction of their length and having their engaging edges shaped to contact with the curved walls of the steam course at an angle thereto.
- 15 9. A rotary engine comprising a stator composed of a drum, opposing heads fitted

to said drum and formed with laterally thick and thin portions arranged to form a sinuous steam course of constant width, a rotor having an annular member housed in said steam course and engaging the walls of the thicker portions of the head, and laterally sliding vanes or pistons carried by the annular member of the rotor and movable across the same into constant engagement with opposite walls of the steam course throughout the length thereof, said vanes or pistons being each composed of a series of independently 35 movable plates, including plates in yieldable or elastic contact with the walls of the steam course and other plates of fixed length and width:

In testimony that I claim the foregoing as 40 my own, I have hereto affixed my signature in the presence of two witnesses,

WILLIAM S. FERGUSON.
